UNITED STATES PATENT OFFICE.

DAVID E. GRAY, OF CORNING, NEW YORK, ASSIGNOR TO CORNING GLASS WORKS, OF CORNING, NEW YORK, A CORPORATION OF NEW YORK.

METHOD OF AND APPARATUS FOR FINISHING BLOWN-GLASS ARTICLES.

1,409,847.

Specification of Letters Patent. Patented Mar. 14, 1922.

Application filed November 3, 1919. Serial No. 335,407.

To all whom it may concern:

Be it known that I, DAVID E. GRAY, a citizen of the United States of America, and a resident of Corning, in the county of Steuben, State of New York, have invented certain new and useful Improvements in Methods of and Apparatus for Finishing Blown-Glass Articles, of which the following is a specification.

10 This invention relates to certain improvements in method of and apparatus for finishing blown glass articles, having comparatively thin walls, of which walls it is desired to remove certain excess portions.

15 Electric lamp bulbs in the shape that they are blown are taken as the particular example of the articles to be treated, and the invention has for its object to provide for the rapid and economical removal of moil

20 from the neck of such a bulb preparatory to subsequent treatment of the bulb. It contemplates a turret mechanism adapted to hold a bulb and position it at several successive stations, means for driving the tur-

25 ret from station to station, the bulb being rotated within the turret, means for heating at the several stations a narrow zone of the neck of the bulb above the moil, whereby the moil will be drawn off of the neck

30 and means whereby the film formed across the neck by such drawing off of the moil will be upturned and melted.

For the purpose above set forth my invention consists in the method hereinafter de-

35 scribed and in the construction, arrangement and combination of the several parts of which the apparatus is composed, as will hereinafter be more fully described and claimed.

40 Referring to the accompanying drawings, in which is shown the preferred embodiment of my invention:—

Figure 1, is a plan view of a machine embodying my invention and adapted to carry out the method herein claimed, certain portions of the machine being removed and showing by dotted lines parts located beneath the table,

45 Figure 2, is a fragmental transverse vertical section showing the turret operating and bulb rotating mechanism,

50 Figure 3, is a view similar to Figure 2, being at right angles thereto and showing the turret locking mechanism,

55 Figure 4, is a vertical section taken on

lines 4—4 of Figure 1, which shows the intermittent drive for rotating the turret,

Figure 5, is a plan view of the mechanism shown in Figure 4,

Figure 6, is a detailed sectional view taken 60 on the lines 6—6 of Figure 1, at station II with a bulb in the turret,

Figure 7, is a view similar to Figure 6, taken on lines 7—7 of Figure 1, at station III, showing a bulb after the moil is 65 dropped off,

Figures 8, to 12, inclusive, illustrate successive steps in removing the moil from the bulb.

I have shown my invention herein in connection with the machine shown in an application filed August 19, 1919, by James Bailey, serially numbered 318,569. For the present purposes the machine may be described as consisting of a rotating turret 70 having thereon a plurality of bulb-holding chucks into which the electric lamp bulbs are adapted to be loaded at what is herein called station I for the treatment forming one of the subject matters of this application, the turret being moved from time to time and arrested with the bulb-holding chucks at certain other stations.

Supported below the top 20, of a suitable table is the main drive shaft 21, driven by a 85 motor 22, by means of a gear train 23, carried by an end plate 20^a of the table and through a friction clutch 24, all of approved construction.

A counter shaft 25, is also mounted below 90 the table top parallel with and in front of the shaft 21, and drives through mitre-gears 26, a vertical shaft 27, having thereon, above the table top, a gear 28, meshing with a gear 29, on the lower end of the hub of the turret 95 30, carrying a plurality (in the present instance, six) bulb-holding heads 31.

Keyed on the shaft 21, adjacent to the end plate of the table is an arm 32, having on its ends rack-sectors 33 and 34; and mounted on a stud projecting from the end plate is a pinion 35, adapted to be intermittently driven by such rack-sectors in the rotation of the shaft 21. The pinion carries a crank pin 36, on which is slidably mounted 100 one end of a pawl 37, the free end of which is provided with a tapered pin 38, projecting from one side thereof. The pawl, which is made in two parts pivoted together at 39, overlies the shafts 21 and 25, and extends 110

between a disk 40, and a wheel 41, both carried on the last named shaft. The disk is provided, in the instant case, with six holes 42, each of which is adapted to receive 5 the pin 38. The pawl carries on one of its sides above the shaft 21, a roller 43. A cam-track 44, is formed upon a segment attached to and forming a part of the arm 32. A coil spring 45, tends to draw the free end 10 of the pawl 37, against the wheel 41, and to thus disengage the pin from the holes in the disk 40, while the cam-track 44, acting through the roller 43, tends to move the pawl in the opposite direction, the arrangement 15 being such that the cam-track is operated for this purpose only on a forward movement of the pawl. The pitch diameters of the rack-sectors 33 and 34, and their lengths, and the pitch-diameter of the pinion 20 35, are such that the pinion will be given a complete rotation on a full rotation of the main shaft 21, although, as will be herein-after described, this movement of the pinion 35, will be intermittent, and be with pause, 25 while the rotation of the shaft 21, will, as stated, be continuous. The throw of the pawl 37, effected by a half rotation of the pinion is such that if the pin thereon is in engagement with a hole in the disk 40, such 30 disk and the shaft 25, will be rotated, in the instant case, through 60° of arc. To prevent overthrow of the pinion 35, notches 47 are formed in the periphery of the pinion, and in these notches a spring-pressed braking roller 48, is adapted to engage. 35

Assuming that the shaft 21 is continuously driven in the operation of the device here described, and that the parts are in the position shown in Figs. 4 and 5, in which the rack-sector 34 is just engaging the pinion 35, and in which the pin 38 is held in one of the holes in the disk 40, by reason of the cam-track 44 engaging the roller 43, the further rotation of the shaft 21 in the direction of the arrow, 45 will turn the pinion 35 through an arc of 180° , the braking roller 48 entering one of the notches 47 at the end of such movement. During this movement, the pawl 37 will be projected forwardly, turning the shaft 25 50 through 60° of arc. At the completion of this movement the rack-sector 34 will go out of mesh with the pinion 35, while the cam-track 44 will be moved away from the roller 43, permitting the spring 45, to withdraw 55 the pin 38 from the hold in the disk, the wheel 41 acting as a stop for this lateral movement of the pawl. Continued rotation of the shaft 21 now causes the rack-sector 33, to mesh with the pinion 35, which will be 60 then given a further movement through 180° , retracting the pawl 37, which at this time, is not in engagement with the disk. After the sector 33 has passed out of mesh 65 with the pinion, the latter is held locked from free movement by the roller 48, and as

the shaft 21 completes its rotation the cam 44 engages the roller 43, and laterally shifts the pawl 37, to cause the pin thereon to enter the hole in the disk 40 following the one which is previously engaged, thus restoring the parts to the position shown, but with an advanced movement of the shaft 25 through 60° . If, however, as just described, the pin 38 does not mesh properly with the next hole in the disk 40, so that the cam 44 by engaging the roller 43 may move the free end of the pawl laterally, the opposite end of the pawl will slide laterally upon the wrist pin, thereby flexing a leaf spring 46, carried by the pawl and engaging the head of the wrist pin. The forward motion of the pawl will then cause the pin 38 on the free end thereof to move about the face of the disk 40 until it registers with the next hole in the disk, which it will then 85 enter under the pressure exerted by the spring 46.

For the purpose of preventing over-running of the turret, a latch mechanism is provided. This, which is shown in Fig. 3, 90 comprises a suitable mounted spring-pressed detent 50, adapted to successively engage notches 51 on the bottom of the hub of the turret 30, the detent being adapted to release the turret at a proper time by means of cam 95 52 fast on shaft 21. The notches are properly located to be engaged by the detent when the bulb-holding heads of the turret are at their several positions. Cooperating with the latch mechanism just described, and 100 suitably secured to one end of the shaft 25, and also connected to the end plate of the table 20, is a friction brake 53, which resists rotary movement of the shaft 25 and of the turret, and thus decreases the impact 105 of the latter against the detent. The hub of the turret is hollow and a hollow standard 56, mounted upon the table top, extends the entire length of the hub, a suitable bearing 55, being located below the hub. Supported 110 by suitable bearings placed at each end of the hollow standard 56 is a vertical shaft 57, which at its upper end carries a gear 58, and which is continuously driven from the main shaft 21, by the bevel gears 59 115 and 60.

The bulb-holding heads 31, are suitably mounted in the turret and at equi-distant points there around, and each is provided with a tubular pinion 61 meshing with the gear 58 and continuously rotated thereby, the pinion having a central opening for the reception of a suitably removable tubular chuck 62. The chucks may be of proper size and shape to support the bulbs to 120 be finished by the machine. As it is desired to remove the moil from the lower end of the neck of the bulb, while the bulb is in the turret, the means for removing the moil are positioned between the top of the table 125 130

and the turret. In view of this fact, it is important that the bulb be carried by the chucks at a uniform distance from the top of the table. In the accompanying drawings, the chucks shown are of the correct design to properly carry the bulb of the type shown, and as such bulb has its side walls formed by a section of a cone, it has been found desirable to make the central bore 63 of each chuck as a cone of proper diameter to engage with the walls of the bulb to support the same at the proper distance from the top of the table. Above such conical bore each chuck has its upper surface beveled outwardly and upwardly, so that if during the operation of the machine a bulb should break, the resultant particles of glass will be led to and fall through the central bore.

20 To prevent particles of glass from clogging the teeth of the gearing on top of the turret, there is provided a cover plate therefor. This cover-plate is composed of segments 64 covering the gears 61 and having 25 flared inner walls which encircle the constantly revolving chucks; and a central plate 65 covering the gear 58. By preference the segmental plates 64 are suitably secured by means of screws passed into bosses formed 30 on the bulb-holding heads 31.

Mechanism has thus been described for holding bulbs and progressively moving them from station to station with a suitable period of arrest at each station, and with 35 the bulbs continuously rotating around their own axis.

A bulb may be loaded by any suitable means into the turret chuck, and this is preferably accomplished by the mechanism 40 shown in the said application of Bailey.

Located beneath the turret at stations I and II are burners 110^a and 110^b, respectively, each supported by a suitable bracket 111, which latter is adjustably secured to the 45 top of the table by the clamp screw 111^a, and the elevating screws 111^b. The burners are so disposed that they each project a flat horizontal sheet of flame at high velocity upon the neck of the bulb held in the chuck 50 at the named stations. The bulb at station I may have the general appearance shown by Fig. 8. The relation of the drive mechanism for the loading tray to the mechanism for the intermittent rotation of the turret 55 is such that, after a bulb has been loaded into a chuck at station I, the bulb will not be moved to the next station for an appreciable time. During this period the flame from the burner pre-heats the neck of the 60 bulb (the bulb being constantly revolving by mechanism previously described) and thus, when the turret is moved forward to the next station, the bulb, having the pre-heated neck, which formerly was at station 65 I, is moved to station II, where the second

burner 110^b is located. A third burner 110^c of similar construction is located at station III, shown by Fig. 7.

The table is provided with apertures 115, 116 and 117, each respectively located at 70 station I, II and III, (see Fig. 1), and below each aperture is located a suitable discharge chute. The chutes 119 and 120 for stations II and III are shown in Figs. 6 and 7. An inclined sheet-metal guard 121 is secured to 75 the top of the table adjacent to stations I and II, and the purpose of this guard is to deflect the broken-off particles of glass, which often accumulate adjacent these stations, towards the apertures thereat. The 80 aperture 117 in the table at station III is provided with a sheet-metal guard 122, comprising two upstanding side walls, and this guard supports a knife 123 which extends across the aperture 117 immediately to one 85 side of the axial lines of the bulb held at station III.

A burner 112 is located above the turret, and adapted to throw a brush flame around the top of the bulb at station III. A vertical burner 113 is located in the aperture 117 at station III to one side of the knife 123, and is arranged in axial alinement with a bulb held in the turret at such station and designed to project a pointed high velocity 95 frame upwardly into the neck of such bulb.

Surrounding the burner 113 and extending across the aperture 117 beneath the knife 123, is an inverted U-shaped hood 124, which has an opening 125 to permit the flame from 100 the burner to pass upwardly therethrough. Thus when the molten drops off the neck of the bulb at station III, as will be hereinafter described, it will be deflected by the knife 123, and the hood 124, and will, therefore, 105 not obstruct the passage of the flame from the jet burner 113, as will be readily understood.

When the high velocity flame from burner 110^b strikes the heated zone formed on the 110 neck of the bulb by burner 110^a, the glass is further heated, whereby the weight of the molten causes the neck to elongate, as shown by Fig. 9 (see Figs. 6 and 8). As the neck of the bulb elongates, the thickness of the 115 glass wall at the heated zone decreases, and if the bulb is then moved to station III, the high velocity flame from burner 110^c, will puncture the thin wall of the elongated section, and the revolution of the bulb will 120 cause the cut to be carried around the bulb, thus cutting off the portion of the bulb below the flame. During this operation there is a tendency of the glass to contract and thus seal the neck by forming a film across 125 the cut-off point, as illustrated by Fig. 10.

It is to destroy this film that the upper burner 112 and the jet-burner 113 are employed. The former heats the air imprisoned in the bulb by the film, and the latter 130

softens and melts such film, and, aided by the pressure of the heated imprisoned air, punctures it. Under these conditions, it has been found that the punctured film will retract and gather around the edges of the neck in a slight bead, as shown by Fig. 11.

The length of the time that the bulbs remain at station I, II and III, the amount of heat thrown out by the burners 110^a, 110^b and 110^c, is such that, under normal conditions, the glass forming the neck of a bulb will be heated to a bright red color, while the bulb is at station I; the heated zone of the neck portions of the bulb will be then softened at station II to such an extent that as soon as the bulb reaches station III, the burner 110 will sever the moil end.

While there has just been described the method by which the excess neck portions 20 of the bulbs are removed under normal conditions, it is to be understood that often these normal conditions do not prevail at the glass factory. Thus, should the bulb be delivered to the turret while it is extremely 25 hot, the burners 110^a and 110^b, at stations I and II, will heat the narrow zone of the neck portion to such an extent that the moil will drop off at station II instead of at station III. If this happens, the moil will fall 30 through the aperture 116 and discharge through the chute 119, and the film across the neck of the bulb will be severed at station III, as before described.

The moil having thus been removed, in 35 station III the bulb is stepped by the turret mechanism through stations IV, V and VI. At the two former stations such other operations may be performed upon it as may be desired, while at station VI it may be 40 removed from the turret, as is described in the said Bailey application.

Having thus described my invention, what I claim and desire to secure by Letters Patent is:—

45 1. In a device of the character described, the combination with a bulb-holder, of means for locally heating a zone around the neck of a bulb held therein to permit the drawing away of the lower end of the neck

thereof, and a burner directing flame into 50 the end of the neck left by the separation of such lower end thereof.

2. The method of finishing a bulb blown from glass which consists of pre-heating the neck portion of the bulb above the moil end 55 to permit a drawing out of such heated portion by the weight of the moil, then severing the drawn-out portion by means of a high velocity flame directed at such pre-heated portion.

60 3. The method of finishing the neck of a bulb which consists of pre-heating the neck portion thereof above the moil to permit a drawing out of such heated portion by the weight of the moil, severing the heated portion by directing at high velocity a narrow flame at such pre-heated portion, and flaring the remaining neck portion while it still retains heat.

65 4. The method of finishing the neck of a 70 bulb which consists of pre-heating the neck portion thereof in a narrow zone to permit a drawing out of such heated portion by the weight of the moil, and cutting said elongated portion by means of a high velocity 75 narrow flame.

5. In a device of the character described, the combination with a bulb-carrying mechanism having periods of rest at a plurality of stations, a burner located at one of such 80 stations and adapted to pre-heat a narrow zone around the neck of a bulb at such station, and a burner located at a succeeding station and adapted to re-heat such pre-heated zone to cause the neck to elongate, 85 and to puncture said elongated neck and sever the same.

6. In a device of the character described, means for puncturing a film formed across 90 the end of a bulb on drawing off a portion of the neck thereof, comprising a burner adapted to heat the air imprisoned within said bulb to expand the same, and a burner directed on said film and adapted to puncture the same.

95 In testimony whereof I have signed my name this 28th day of October, 1919.

DAVID E. GRAY.
